UNITED STATES PATENT OFFICE.

CHARLES E. BENNETT, OF DECATUR, GEORGIA.

FUSE.

Application filed September 28, 1926. Serial No. 137,309.

My invention relates to fuses, and particularly to a fuse for breaking high potential current. The object of my invention is to provide a simple, economical fuse structure which will afford efficient protection to equipment in power lines, and may be safely substituted for the expensive, and even dangerous, oil circuit breakers now in general use for this purpose in circuits of 2500 volts to 132,000 volts or over with which particularly the present invention deals. Certain features of the invention are applicable to other structures and devices than fuses, strictly so called, and these broader applications of the invention are to be understood to fall within the scope of the subjoined claims.

In the accompanying drawings—

Fig. 1 is a broken section through a fuse embodying my invention in a construction suitable for voltages up to about 44,000 volts; and

Fig. 2 is a similar view through a fuse appropriate for higher voltages.

The constructions shown are merely illustrative of my invention and may be variously modified, while still embodying the characteristics of operation and construction which I claim as my invention.

Referring to Fig. 1 dealing with a construction appropriate for voltages up to 44,000, I have shown the fuse strip or wire 15 attached at its opposite ends to similar contact ferrules 16 and 17. Each ferrule is spool-shaped, the end flanges 18 and 19 thereof spanning a spring terminal contact (not shown) which grips the barrel or body of the ferrule. Intermediate the end flanges 18 and 19 the ferrule is provided with an interior transverse web 20 centrally apertured at 21 to permit the passage of the fuse end therethrough. The projecting fuse end 22 is offset against the outer face of the web 20, against which it is clamped by a screw plug 23, through an interposed metallic washer 24. Preferably a tight fitting washer 25 of rubber, or other displaceable material, is interposed between the plug 23 and washer 24 to seal the joint against the escape of gases which form on the blowing of the fuse.

Encasing the fuse strip throughout its length between the ferrules 16 and 17, is a renewable casing comprising a strong walled tube 26 of non-shattering but rupturable, insulating material which is non-inflam-

mable under operating conditions and of such character that dangerous carbonization of the wall does not occur on the blowing of the fuse. I have found poor grade rubber a most satisfactory material since its fillers 60 render it in effect non-inflammable under operating conditions without losing the desired yielding and flexible characteristics of the casing.

Each end of the casing 26 is provided with 65 a head flange 27 against which bears a screw plug 28, by means of which the tube end is firmly clamped against the diaphragm 20 with the small bore of the casing in register with the fuse aperture 21 in the diaphragm. 70

The pressure of the metallic gases generated within the casing by the burning of the fuse is very high due to the restricted cross-section of the casing bore. The end seals, and the wall, of the renewable casing are 75 accordingly strong: for example, sufficiently strong to withstand an internal pressure of about 100 pounds per square inch. When the fuse blows, the gas pressure within the casing exceeds this and the casing ruptures 80 at its weakest point. The escaping hot gases may cause damage unless properly directed and may even cause the establishment of an arc between the fuse terminals and exterior to the casing. I prefer therefore to definitely locate a weak spot in the tube wall. This may be accomplished in various ways. For example, in Fig. 1 I have indicated a minute puncture 29 extending through the wall of the casing at a point approximately 85 midway of its length. A spring band clip 30 normally closes the puncture, but is projected from the casing by the escaping gas. The rupture of the casing therefore occurs at this weakened point, and the hot gas escapes in the direction of the puncture. It 90 may thus be definitely controlled. When rupture occurs, the ferrules, terminals and adjacent equipment remain uninjured by arc or gas. No arc between the terminals becomes established and while the casing is destroyed, it is inexpensive and is readily and 95 simply replaced. Under no circumstances can a dangerous explosion occur as is frequently the case with oil circuit breakers. 100

The construction shown in Fig. 2 is adapted to heavy voltage duty. A fuse carrying current of 44,000 volts and over is subject to disintegration as the result of corona action. To protect the fuse against this phe- 110

nomenon, I provide a corona shield by surrounding the fuse casing 31 by a second casing 32 of similar material, and filling the annular space therebetween with some high 5 resistance fluid 33 (such e. g. as distilled water) which is non-injurious to the material of the casings, and carries enough current to serve as a corona shield. It may also be of such character as to aid in extinguishing the flame or arc on rupture of the fuse 10 casing.

The ferrule construction is adapted to such an arrangement. Thus, the flange 34 at the tube end of the ferrule barrel 35 is 15 extended to form a housing for the head 36 of the outer tube 32, the metal washer 37 and screw plug 38. The metal washer 37 lies against the end of the ferrule body, and its central boss 39 surrounds the inner tube 31 20 and enters the end of the tube 32, thus centering the tubes with respect to each other. This washer also establishes electrical connection between the fluid corona shield 33 and the ferrule. The screw plug 38 bears 25 against the head 36 of the outer tube and clamps it against the washer 37 and ferrule in a firm liquid sealed joint.

The head of the inner tube 31 is pressed against the outer face of the washer 37 by 30 the screw plug 40, which also clamps the offset fuse end between the washers 41 and 42 which are in contact with the ferrule.

While the wall of the tube 31 may be weakened at some point as at X, to determine 35 a rupture point, obviously no puncture can be permitted which would admit the surrounding liquid to the interior of the tube. As a matter of fact a rupture point is of relatively little importance since the 40 flame from the fuse tube at once converts the liquid 33 into vapor, and while this vapor may have sufficient pressure to rupture the outer casing, it serves in any event to suppress the flame and render the rupture 45 innocuous.

I have mentioned above the fact that the tubes 26, 31, and preferably also the corona casing 32, are of non-inflammable material, and I have mentioned low grade rubber as 50 suitable for such use. Rubber of this character, however, deteriorates when subjected to the action of the elements. I therefore propose to protect the casings by a very thin skin 43 of synthetic rubber which will 55 withstand sunlight, etc., and screen the low grade body material of the tube from actinic rays and other deteriorating influences.

When excessive current is imposed on the fuse, the fuse wire or strip is consumed 60 throughout the major portion of its length. A very heavy gas pressure builds up within the casing and ruptures the latter. On the relatively low voltage fuses, excessive pressure ruptures the casing at its weakened 65 point 29, and the hot gases escape at this

point. There is no arc formation, however, between the contacts with which the ferrules 16 and 17 are engaged, and the circuit is promptly broken. It is an easy matter to replace the rubber casing and the fuse by 70 unscrewing the plugs on opposite sides of the ferrule diaphragm. On the high voltage fuses in which the fuse casing is surrounded by the corona shield liquid, the latter helps to chill the hot gases that escape the fuse 75 casing on rupture of the latter and creates a condition which aids in extinguishing any arc which might tend to form.

The exact explanation of what occurs on the blowing of the fuse cannot now be given 80 by reason of the rapidity of action and the consequent difficulties of observation. It is my present belief however, that the sudden escape of the gases from the casing not only creates, by jet action, a partial vacuum 85 within the casing (and a vacuum is inimical to arc maintenance) but also exhausts practically all of the fuse metal in gaseous condition, with the result that on condensation of the slight amount of metallic gas that 90 remains in the casing the metallic deposit on the inner wall thereof is so slight and the metallic particles so separated that no current path is established thereby between the opposite end ferrules. The charring of the 95 inner wall of the casing by the flame is slight by reason of the character of the material of the casing which, in large part, is non-carbonizing under the conditions of fuse 100 rupture.

It is possible that other insulating material could be used for the casing, if of sufficient strength to withstand the heavy pressures generated incident to the blowing of the fuse and otherwise suitable, but I prefer low grade, substantially non-inflammable rubber composition, by reason of its economy, its non-shattering character on rupture, its flexibility and resilience, and the facility with which it may be jointed to the ferrules to form tight seals. 105

Of course the size of the fuse wire will vary with the current that it must carry, and the strength of the casing walls must vary in accordance with the internal pressures likely to be encountered. The length of the fuses and of their casings will vary with the voltage. For example, for a 2500 volt fuse an over-all length of 12 inches will suffice, while for a 132,000 volt fuse an over-all length of approximately 4 feet is desirable. It will be realized that the initial expense of fuses of this character is negligible as compared with the equipment now in general use for like service. Yet I have found that fuses of the construction stated function reliably without danger to surrounding equipment or fuse terminals. 115 120 125

I have shown the fuse casing as a renewable element, along with the fuse strip, be- 130

tween the end ferrules. It may be preferable to eliminate the human factor by connecting the casing and fuse permanently to the ferrules so that the entire fuse must be discarded on rupture. Assurance of proper end seals may thus be obtained.

As I have stated at the outset, the particular construction of the fuse elements may be varied in many ways without departing 10 from what I claim as my invention.

I claim—

1. In a high voltage fuse, a fuse casing sealed at its opposite ends against rupture thereat on the blowing of the fuse having a 15 bore of restricted cross-section to afford a fuse chamber of restricted dimensions, said casing being formed of non-inflammable yieldable, flexible insulating material susceptible to rupture at a point between said 20 ends under high internal pressure.

2. In a high voltage fuse, a fuse casing sealed at its opposite ends against rupture thereat on the blowing of the fuse having a bore of restricted cross-section to afford 25 a fuse chamber of restricted dimensions, said casing being formed of non-inflammable yieldable, flexible insulating material susceptible to rupture at a point between said 30 ends under high internal pressure, said casing being weakened at a point intermediate its ends to locate a definite rupture point.

3. A high voltage fuse comprising a pair of end contact ferrules, a fuse element extending therebetween, and a fuse casing of 35 non-inflammable flexible insulating material susceptible to rupture under heavy internal stresses, said casing having a fuse chamber of restricted cross-sectional area and being sealed at said ferrules against gas 40 escape at rupturing pressure.

4. In a high voltage fuse, a pair of metallic end ferrules, a fuse element in electrical connection therewith, a sealed fuse casing 45 of non-inflammable flexible insulating material rupturing on heavy internal pressure, and secured to the ferrules to prevent gas escape at the opposite ends of the structure

in the direction of the casing bore on rupture of the casing.

5. In a high voltage fuse, a pair of metallic end ferrules, a fuse element in electrical connection therewith, and a tubular fuse casing of non-inflammable flexible rubber composition capable of withstanding heavy internal pressure and secured to the ferrules 55 to prevent gas escape at the opposite ends of the structure.

6. In a high voltage fuse, a pair of metallic end ferrules, a fuse element in electrical connection therewith, and a flexible tubular 60 fuse casing of non-inflammable rubber composition capable of withstanding heavy internal pressure and secured to the ferrules to prevent gas escape at the opposite ends 65 of the structure, said flexible casing having a protective skin adapted to prevent deterioration of the casing on exposure to the elements.

7. As an element of a fuse structure, an 70 end sealed tubular fuse casing of non-inflammable flexible insulating material capable of withstanding high internal stresses.

8. As an element of a fuse structure, a sealed tubular fuse casing of yieldable, non-inflammable insulating material capable of 75 withstanding high internal stresses, but weakened at a predetermined rupture point between its ends.

9. A fuse comprising a fuse element, an insulating casing therefor, and a liquid 80 corona shield surrounding said casing.

10. A fuse structure comprising a pair of concentric insulating casings, a fuse element within the inner casing, and a liquid corona 85 shield in the annular space between the casings.

11. A fuse structure comprising a pair of fuse terminals, a fuse extending therebetween, and a corona shield in electrical contact with said terminals. 90

In testimony whereof I have signed my name to this specification.

CHARLES E. BENNETT
